FIG 7

UNITED STATES PATENT OFFICE.

ZACHARY TAYLOR RENO, OF NEW ORLEANS, LOUISIANA.

SLIDE-VALVE.

SPECIFICATION forming part of Letters Patent No. 348,777, dated September 7, 1886.

Application filed December 21, 1885. Serial No. 180,363. (No model.)

To all whom it may concern:

Be it known that I, ZACHARY TAYLOR RENO, a citizen of the United States, residing at New Orleans, in the parish of Orleans and State of 5 Louisiana, have invented a new and useful Improvement in Slide-Valves for Steam-Engines, of which the following is a specification.

My invention relates to improvements in slide-valves and the manner of admitting steam 10 to them, so that the water of condensation may largely free itself previous to passing through the slide-valve in the cylinder; also, to provide a balanced or nearly balanced slide-valve having a central steam-opening through it and 15 having steam-pressure top and bottom of the valve which works over the steam-ports and allows the steam to exhaust into the steam-chest, into which high steam does not enter; also, to provide a valve and steam-ports in 20 valve-seat of engine-cylinder that will permit a rapid discharge of exhaust-steam, which is especially desirable in locomotives and high-speed steam-engines. These objects are obtained by the mechanism shown in the accompanying drawings, in which like letters refer 25 to like parts.

Figure 1 represents a longitudinal section through the slide-valve, the steam-chest, and steam-ports of a steam-engine cylinder. Fig. 30 2 is a face view of valve-seat of engine-cylinder. Fig. 3 is the face view of the bottom of the slide-valve. Fig. 4 is a horizontal section of slide through line A. B, Fig. 1, and shows, also, the valve-seat under the valve with 35 the relative position of valve and steam-ports in valve-seat at the end of extreme throw of valve. Fig. 5 is a similar view as Fig. 4, but shows the valve just beginning to admit steam and the relative size of exhaust-opening. Fig. 6 shows a longitudinal section of 40 valve with a regulating-cock through it. Fig. 7 is a longitudinal section of part of a steam-engine cylinder and piston and arrangement of double slide-valves.

45 Steam enters steam-pipe C, Fig. 1. At D is a short pipe turned and fitted so it will slide in a bored hole of steam-chest cover E. The sliding pipe D is solid at bottom G, and forms a piston. When steam is lightly turned on 50 pipe C, the condensed water in the pipe is

driven out through holes H and drip-pipe I. As the pressure increases, the piston D descends, overcoming the resistance of the spiral spring J until the holes H in pipe D open into the chamber K, when the entrance to pipe I 55 is cut off and steam enters chamber K, presses on piston L, which works in cylinder j, formed by lower part of steam-chest cover E, and a steam-joint is made by packing-rings M. The lower face of piston L presses an upper face of 60 the valve N. The steam passes through holes k in piston L, thence through hole O in valve N. The lower part of hole O is enlarged to just the extent that is necessary to make its area slightly less than the area of the inside of 65 the piston L, so that the valve N may be nearly balanced, but held down by the greater pressure on top.

At P Q are the ports through which pass alternately high and exhaust steam. The 70 steam exhausts into the steam-chest R and passes out through hole S.

At Fig. 4 the relative positions of valve N and openings P and Q in valve-seat S are shown when wide open. The steam is entering opening Q and exhausting out of opening P.

At Fig. 5 the relative positions of valve N and valve-seat S are shown when steam commences to enter and steam begins to exhaust. 80 It will be seen that by the shapes of the openings in valve N and the openings P and Q in valve-seat that at all parts of the stroke the exhaust is larger than the steam-opening, even if the valve be set without any lead on the 85 exhaust. This is obtained by the combined curved and straight lines on same opening in valve-seat S, and the circular or curved shaped opening O in valve N.

I do not confine myself to using the herein- 90 described valve N in combination with the described steam-openings in valve and valve-seat, as the valve N can be used equally as well with parallelogram or other shaped openings in valve and valve-seat; but I prefer the 95 herein-described shapes. Nor do I confine myself to using the described balance-valve N in combination with the described mechanism for removing condensed water from steam- pipe, as the valve N can be worked advan- 100

stageously without such mechanism as well as with it, as shown at Fig. 7, in which the valve N of Figs. 1, 3, 4, 5 becomes valve Y.

Fig. 6 shows a cock, T, through hole O in valve N.

U is a socket-wrench handle fastened to cock T, and passes through a stuffing-box in end of steam-chest, with a handle outside to regulate at will the flow of steam immediately 10 at the steam-openings P and Q.

V is the valve-stem.

This cock T in valve N will not be used generally; but I desire to show and describe the arrangement if I should ever desire to use it.

Fig. 7 shows part of a steam-engine cylinder, W, and piston X, and arranged for double valves Y Y and double valve-pistons Z Z. The valves Y Y are connected together in any suitable way, as at a. The steam-pipe b branches to each steam-chest cover c. The steam passes in through holes d and holes e in valves Y.

The drawings at Fig. 7 show the steam-port b receiving full opening of steam. The port g is full open, through which the exhaust- 25 steam is passing out into the steam-chest h,

and thence escapes through hole i into escape-pipe.

What I claim, and desire to secure by Letters Patent, is—

1. A solid valve provided with a direct continuous steam-passage through it from top to bottom face, in combination with a piston and cylinder over the valve, the piston resting on top face of valve, substantially as described. 30

2. A solid slide-valve having a direct continuous central steam-passage through it, in combination with steam-ports in valve-seat provided with straight and curved edges to each port for the purpose of obtaining a free 40 and rapid exhaust, substantially as described.

3. The herein-described slide-valve N, in combination with the piston L, the cylinder j, the spring J, and the piston D, provided with the holes H to allow the water of condensation to pass out of steam-pipe through 45 drip-pipe I, substantially as described.

ZACHARY TAYLOR RENO.
